(74) Attorney, Agent, or Firm — Kimberly-Clark Worldwide, Inc.

(57) **CLAIM**

We claim the ornamental design for an absorbent article, as shown and described.

DESCRIPTION

FIG. 1 is a perspective view of an absorbent article; FIG. 2 is a top view of the absorbent article of FIG. 1; FIG. 3 is a back view of the absorbent article of FIG. 1; FIG. 4 is a right side view of the absorbent article of FIG. 1, wherein the left side view is a mirror image of FIG. 4; FIG. 5 is a first end view of the absorbent article of FIG. 1; and, FIG. 6 is a second end view of the absorbent article of FIG. 1.

The dash-dot-dash broken lines shown in FIGS. 1-3 as well as the broken lines that are adjacent to the claimed surface in FIGS. 1-2 illustrate boundary lines that form no part of the claim. The additional broken lines shown in FIGS. 1-6 illustrate portions of the absorbent article that form no part of the claimed design.

1 Claim, 3 Drawing Sheets
